BOILER CONSTRUCTION

Filed May 28, 1934

Technical drawing of a heat exchanger assembly, labeled Fig. 1. The diagram shows a large rectangular heat exchanger body with a coil of tubes inside. The tubes are labeled 16 and 17. Various pipes and valves are connected to the top and side of the heat exchanger. A vertical pipe on the right is labeled 11, 12, 2, 6, and 11. A horizontal pipe at the bottom is labeled 3, 15, 10, 8, and 11. A valve at the top left is labeled 1. A pressure gauge is connected to the top right. A handwritten label 'Fig. 1.' is in the top left corner.

BOILER CONSTRUCTION

Sidney E. Parker, Los Angeles, Calif., assignor to
Charles J. Mund, Los Angeles, Calif.

Application May 28, 1934, Serial No. 727,920

4 Claims. (Cl. 122—250)

This invention relates to a boiler construction and the prime object is to provide a tubular boiler frame or supporting structure, this frame acting as a conduit for the water supply which prevents overheating and destruction of the frame.

Another object is to provide a novel coil mount whereby the coil can be easily and quickly removed for purposes of repair or replacement.

A further object is to provide a novel frame structure which can be easily cleaned when necessary.

Other objects, advantages and features of invention may appear from the accompanying drawing, the subjoined detailed description and the appended claims.

In the drawing

Figure 1 is a side elevation of my boiler construction with the housing or cover removed.

Figure 2 is a longitudinal sectional view of one of the end frame members.

Referring more particularly to the drawing, the numeral 1 indicates a boiler drum of usual and well-known construction and this boiler is supplied with hot water or steam from a double coil 2. A suitable burner 3 is provided below the coil for the purpose of heating the water which moves thru the coil. The burner is of usual and well known construction and may be either gas, oil or the like.

Boilers of the type disclosed in this invention are enclosed in a housing and consequently, the supports for the boiler drum are subject to a rather intense heat. This heat causes rapid oxidation and the supporting structure will fail after a comparatively short length of time.

The supporting frame for the boiler drum 1 comprises two end members 4, 5, each of which comprises a vertical pipe 6, a pair of short nipples 7, 7 attached to the bottom of the pipe 6 and a pair of vertical pipe sections 8, 8 which form legs to support the boiler drum. The pipes 8 are closed at the bottom by a cap 9. Suitable pipe fittings of standard construction connect the various pipe sections and nipples to form a conduit or passage-way which is filled with water, as will be subsequently described.

A horizontal pipe 10 connects the end frames 4 and 5 and the water intake pipe 11 extends into this horizontal pipe. It will be evident, therefore, that both of the frame members, as well as the horizontal pipe 10 will be completely filled with water from the source of supply. A pipe coupling 11' extends from the top of the pipe 6 into the boiler drum, thereby completing the circuit for the water.

A threaded plug 12 is provided at the top of each of the pipes 6 and a second threaded plug 13 is provided at the bottom and when these are removed, the pipe 6 can be quickly and easily cleaned. A plug 14 is also provided in the end of the horizontal pipe 10 for the purpose of cleaning this pipe, when necessary.

The double coil 2 is connected to the pipe 10 by a T 15 and the upper ends of the coils extend into the bottom of the boiler drum 1 at 16 and 17. It will be evident that the coil 2 can be removed for the purposes of replacement or repair by merely removing the fittings at the top and bottom of the coils, all of which are easily accessible.

The circulation of water is an upward one thru the coils 2, thence into the boiler drum 1, thence downwardly thru the vertical pipe 6, thence into the horizontal pipe 10 and into the bottom of the coils. Sediment is dropped in the horizontal pipe 10 and can be removed when necessary by opening the stop cock or boiler blow out valve attached to one end of pipe 10.

Having described my invention, I claim:

1. In a boiler construction comprising a boiler drum, a tubular frame comprising a pair of end members, each of said end members comprising a vertical pipe, a pair of pipe legs attached to the bottom of said vertical pipe, said vertical pipe extending into the boiler drum at the upper end thereof, a horizontal pipe connecting said end members, and a water intake extending into said horizontal pipe, screw plugs in the top and bottom of said vertical pipes and a screw plug in the end of said horizontal pipe.

2. In a boiler construction comprising a boiler drum, a tubular frame supporting said boiler, said tubular frame comprising a pair of end members, a vertical pipe in each of the end members, said vertical pipes extending into the boiler drum at the upper ends thereof, pipe legs attached to said vertical pipes, a horizontal pipe connecting the end members and coupled thereto, a coil below the boiler drum, the upper end of said coil extending into the boiler drum, and the lower end of said coil extending into the horizontal pipe, cleaning plugs in the top and bottom of said vertical pipes and a cleaning plug in the end of said horizontal pipe.

3. In a boiler construction comprising a boiler drum, a tubular frame supporting said boiler, said tubular frame comprising a pair of end members, a vertical pipe in each of the end members, said vertical pipes extending into the boiler drum at the upper ends thereof, pipe legs attached to said vertical pipes, a horizontal pipe

connecting the end members and coupled thereto, a coil below the boiler drum, a T fitting in the horizontal pipe, said coil being attached to the T fitting, a fitting at the top of the coil, said fitting extending into the bottom of the boiler drum and heating means for said coil, cleaning plugs in the top and bottom of said vertical pipes and a cleaning plug in the end of said horizontal pipe.

4. In a boiler construction comprising a boiler drum, a tubular frame comprising a pair of end

members, each of said end members comprising a vertical pipe, a pair of pipe legs attached to the bottom of said vertical pipe, said vertical pipe extending into the boiler drum at the upper end thereof, a horizontal pipe connecting said members, water intake means, cleaning plugs in the tops and bottoms of said vertical pipes, and a cleaning plug in the end of said horizontal pipe.
